UNITED STATES PATENT OFFICE.

GEORGE M. NORTON, OF MINNEAPOLIS, MINNESOTA.

DESIGN FOR A CIGAR LIGHTER.

Application filed December 24, 1927. Serial No. 24,629. Term of patent 7 years.

To all whom it may concern:

Be it known that I, GEORGE M. NORTON, a citizen of the United States, a resident of Minneapolis, county of Hennepin, and State of Minnesota, have invented a new, original, and ornamental Design for Cigar Lighters, of which the following is a specification, reference being had to the accompanying drawings, forming part thereof.

The figure of the drawing shows a perspective view of a cigar lighter embodying my design.

I claim:

The ornamental design for a cigar lighter, as shown.

GEORGE M. NORTON.
